UNITED STATES PATENT OFFICE.

CHARLES A. SMITH, OF JACKSON, MICHIGAN.

FEEDING DEVICE FOR MIDDLENS-PURIFIERS.

SPECIFICATION forming part of Letters Patent No. 339,029, dated March 30, 1886.

Application filed July 9, 1884. Serial No. 137,242. (No model.)

To all whom it may concern:

Be it known that I, CHARLES A. SMITH, a citizen of the United States, residing at Jackson, in the county of Jackson and State of Michigan, have invented certain new and useful Improvements in Feeding Devices for Middlens-Purifiers, of which the following is a specification, reference being had therein to the accompanying drawings.

10 Figure 1 is a side elevation of one end of a middlings-purifier having my invention applied thereto. Fig. 2 is a detached view, enlarged, of my invention, part of the machine being in elevation, taken on line $x x$, Fig. 4.

15 Fig. 3 is a vertical longitudinal section taken on line $y y$, Fig. 4. Fig. 4 is a plan view taken on line $z z$, Fig. 2. Fig. 5 is a vertical longitudinal section of a part, showing a modification.

20 A A are the front posts; B B, horizontal girts; and a a the casing, which may be of any usual or approved construction.

C is a front girt crossing the machine about midway between its top and bottom, and D D

25 d d indicate the shaker and cloth-bars, these latter parts being preferably of the construction shown in Patent No. 259,639, to Milford Harmon; but, as this feeding mechanism is adapted for use upon many forms of shakers,

30 I do not wish to be limited to the construction herein shown and referred to. The shaker may be suspended upon pendulum-links and reciprocated by means of an eccentric-shaft, E, mounted in bearings e, (attached to the vertical posts A A of the purifier,) and pitmen F, connecting the shaft with a transverse bar, f, framed at its ends into the side pieces of the shaker.

40 I will now proceed to describe in detail the feeding mechanism or devices to which this invention relates.

G is a bottom board, the forward ends of which are expanded, as at g g, Figs. 2 and 4, and secured to the upper edges of the sides of

45 the shaker-frame, so as to travel therewith. The upper surface of this bottom board is inclined, so that its lower edge, which is arranged near the head end of the shaker, is the lowest.

50 H is the front vertical wall; J', the rear wall, and i i the side boards.

K is the top or deck, making a practically-

inclosed box, except that the front board or wall, H, is narrower than either the sides or the rear wall, so as to leave a narrow throat, 55 h, (see Figs. 2 and 3,) between the lower edge of the front board, H, and the bottom board, G.

J is a vibrating carrier, pivoted to the sides at j j. This vibrating carrier J is of such length as to fit closely inside of the sides i i, 60 and is preferably of such width as to project through the throat h, to receive plates or bars l l, which are attached to the under surface of this vibrating carrier at its sides and project in front of and beyond the sides i i. 65

L L are plates or hangers attached to the upper face of the deck K, directly above the bars l l, with which they are connected by elastic or yielding links, each consisting, in this instance, of an eyebolt, M, and spiral 70 spring m, so that by turning the thumb-nuts on the upper ends of the eyebolts the upward lift or pull upon the vibrating carrier J can be regulated at the will of the operator.

N is a spout-section attached to and projecting down through the deck K. 75

O is a feeding-spout communicating at its upper end with some convenient source of supply and projecting thence downwardly into the upper open end of the spout-section N. 80 The feeding-spout is secured to the purifier.

From an examination of the drawings it will be readily understood that as the shaker and these feeding devices vibrate, the middlings, which are fed in through the spout O 85 and fall upon the vibrating carrier J, will be fed through the throat which exists between the upper surface of this vibrating carrier and the lower edge of the front board or wall, H, whenever the tension of the spiral springs m 90 is properly regulated, and it will also be understood that by means of the thumb-nuts n n the width of this discharge-throat can be varied at the will of the operator as the existing conditions of material and the work to be 95 done may render desirable. Of course the width of this discharge-throat will depend upon both the tension of the springs and the weight of the middlings upon the vibrating carrier J, from which it will be understood that any increase in the accumulation of middlings upon this carrier will increase the width of the throat (unless the position of the thumb-nuts be changed) and thus gradually work off

100

any such accumulation, after which the throat will be again narrowed, so that even with the diminished supply the middlings will still be fed across the entire width of the shaker in a sheet of practically uniform thickness throughout. So, also, in case any foreign substance or lumps of middlings should get into the inclosed box this carrier can swing down and permit its escape, after which it will return to its normal position.

In Fig. 5 I have illustrated a modification in which the parts are substantially the same as are shown in the other figures, except that the board J is at its rear end hinged near the deck or flooring K, and is provided with an opening, J^2 , immediately below the spout-section N, and of such size as to permit the middlings to flow freely through such opening into the space between the inclined board J and the bottom board, G. The forward end of this inclined board also projects through the longitudinal slot h and is connected with the plates or hangers L by means of a bolt, M, threaded at its upper end and provided with a thumb-nut, n^2 . A spiral spring, m, surrounds this bolt with its upper end engaging with the under side of the bar L and its lower end bearing against the upper surface of the board J. There are of course corresponding bolts and springs at each side of the shaker, so that the width of the throat between the lower edge of this inclined board and the adjacent edge of the bottom or of a rib upon the bottom board can be regulated with great accuracy to determine the rate of feed, and at the same time the width of this throat can be increased by any unusual increase of pressure upon the bed of middlings between the board J and the bottom board, G, to permit the passage of any lumps of material or foreign substance which may happen to be mixed with the middlings. This feeder will properly deliver middlings to the screen without producing that objectionable attrition or rubbing of particles against one another which is liable to result from the use of rollers or any other devices in which the feeding is effected by either a rolling or vibrating movement of one wall of the throat relative to its opposing wall, which attrition is liable to injure the middlings by reducing their "sharpness."

I do not wish to be limited to the use of springs for moving the discharging edge—that is to say, the front edge of the vibrating carrier—upward toward the lower edge of the front vertical wall or side board, because under some circumstances a counterbalancing-weight might be used for that purpose.

It will be understood that in all of the constructions shown there is a feeding-throat formed between the front edge of a vibrating board and an adjacent parallel edge of the feeder, a short spout-section attached to and carried by the body of the feeder, and another spout supported independently of the vibrating parts of the feeder. It will also be seen that in all of the constructions shown the vi-

brating board which forms one side or wall of the throat is supported at one edge by means of adjusting devices, and can also yield to permit a more rapid feeding of the material in case of an increased pressure or supply, and also to permit the passage of any foreign substances. Of course many other forms of springs or elastic or yielding links might be substituted for those shown by any mechanic who is skilled in the art of constructing such devices.

What I claim is—

1. In a vibrating feeder, the combination of an inclosed box, a movable carrier situated above the bottom of said box and adapted to adjust the width of the throat through which the middlings are discharged, and a tension device which regulates the position of the movable carrier and therefore the width of the discharge-throat, but which permits the carrier to move when subject to unusual pressure, substantially as set forth. 80

2. In a vibrating feeder, the combination of an inclosed box having an upper board and a lower board, between which the material passes, and of which one is pivoted and has one edge movable about its pivot to increase or diminish the throat through which material passes, means for adjusting one edge of the movable board relative to the adjacent portion of the other board, and a spring applied to the movable board and adapted to maintain a uniform width of the feeding-throat, but which permits the edge of the movable board to yield under pressure, substantially as set forth. 90

3. In a vibrating feeder, the combination of an inclosed box having an upper board and a lower board, between which the material passes, and of which one is pivoted and has one edge movable about its pivot to increase or diminish the throat through which material passes, the spout-section supported upon the inclosed box and opening into the box, and a feed-spout of less diameter than the spout-section, and having its lower end arranged within the spout-section and supported independently of the vibrating parts of the feeder, substantially as set forth. 105

4. In a vibrating feeder, the combination of an inclosed box having four vertical walls and a closed top, the inclined vibrating board arranged within the box to receive and support the middlings, a horizontal throat at the front edge of the vibrating board for the passage of the middlings, the spout-section connected to the top of the inclosed box and adapted to receive the material and deliver it to the interior of the box, and spring devices which support the front edge of the inclosed board and permit it to yield under the weight of the middlings, substantially as set forth. 120

5. In a vibrating feeder, the combination of an inclosed box, the vibrating board arranged within the box, a discharging-throat at the front edge of the vibrating board, the adjusting-bolts and the springs connecting the ad-

justing-bolts with the vibrating board to regulate the width of the feeding-throat, substantially as set forth.

6. In a vibrating feeder, the combination of an inclosed box, the vibrating board within the box, a discharging-throat at the front edge of the vibrating board, devices for adjusting vertically the front edge of the vibrating board, a spout-section attached to and vibrating with the inclosed box, a feed-spout of less diameter than the spout-section and having its lower end arranged within the spout-section and supported independently of the inclosed vibrating box, substantially as set forth.

7. In a vibrating feeder, the combination, 15 with the vibrating carrier, the front vertical wall, the rear wall, and the side walls, of the hangers, the bars projecting from the vibrating carrier, and the yielding links connecting the hangers with the projecting bars, substantially as set forth. 20

In testimony whereof I affix my signature in presence of two witnesses.

CHARLES A. SMITH.
